UNITED STATES PATENT OFFICE.

HENRY D. SWIFT AND DANIEL WHEELER SWIFT, OF WORCESTER,
MASSACHUSETTS.

PRINTING-MACHINE.

SPECIFICATION forming part of Letters Patent No. 585,296, dated June 29, 1897.

Application filed October 29, 1892. Serial No. 450,401. (No model.)

To all whom it may concern.

Be it known that we, HENRY D. SWIFT and DANIEL WHEELER SWIFT, citizens of the United States, residing at Worcester, in the 5 county of Worcester and State of Massachusetts, have invented a new and useful Improvement in Printing-Presses, of which the following is a specification, reference being had to the accompanying drawings, forming 10 a part of the same.

Our present invention relates to that class of printing-presses known as "rotary," which are arranged to print single sheets, instead of a continuous web, of paper; and it 15 relates particularly to that part of the operative mechanism by which the paper is fed to and taken off from the impression-cylinder.

The accompanying drawings represent a printing-press especially designed for printing envelop-blanks and embodying our invention.

Figure 1 is a front view of the machine. Fig. 2 is a side view showing the left side as represented in Fig. 1. Fig. 3 is an end view 25 of the impression-cylinder looking in the direction of the arrow 1, Fig. 1. Figs. 4 to 9, inclusive, represent sectional views of the impression-cylinder on line 4 4, looking in the direction of the arrow 2, Fig. 1, and designed to show the several positions assumed by the grippers during a revolution of the impression-cylinder. Fig. 4 shows the grippers as nearly closed upon the paper blank which has been raised from a pile of blanks 30 by the pneumatic finger. Fig. 5 represents the grippers as closed upon the paper blank. Fig. 6 shows the grippers closed and moved into alinement with the surface of the cylinder. Fig. 7 represents the grippers as carried out in order to raise the printed sheet 35 from the cylinder and allow the ends of the fly-fingers to pass beneath it. Fig. 8 represents the grippers open to release the sheet. Fig. 9 represents the grippers open with the 40 outer jaw moved in toward the center of the cylinder to clear the paper blank held by the pneumatic finger and with the inner jaw moved out so the face of the jaw will correspond with the lower surface of the pneumatic finger when the grippers arrive at the 45

position shown in Fig. 4. Fig. 10 is an end view of the impression-cylinder looking in the direction of the arrow 3, Fig. 1. Fig. 11 is a top view of the feeding-table and pneumatic finger and showing the pivoted "separator." Fig. 12 is a front view of a portion of the separator. Fig. 13 is a sectional view of the same on line 13 13, Fig. 12. Fig. 14 represents in central sectional view a portion of the air-pump cylinder and valve by which 50 air is admitted to break the vacuum. Fig. 15 is a central sectional view of the pneumatic finger on line 15 15, Fig. 16. Fig. 16 is a view of the under side of the pneumatic finger with a portion broken away to disclose 55 the interior air-passages. Fig. 17 shows in detail the operative mechanism for vibrating the fly-fingers, and Fig. 18 is a perspective view of the grippers and gripper-shafts.

Similar letters refer to similar parts in the 60 different figures.

Referring to the drawings, A denotes the frame of the machine, B the type-cylinder, and C the impression-cylinder, journaled in boxes B' and C'. The boxes B', of which 65 only one is shown, are fixed upon the frame, and the boxes C' are united to the boxes B' by right and left hand screw-threaded bolts C², by which they are adjusted to bring the axes of the cylinders parallel and the proper 70 distance apart.

The cylinders are geared together by gear-wheels C³ and C⁴, attached to each end of the cylinders, the gears upon one of the cylinders being adjustable by set-screws C⁵ and slots 75 C⁶, so the teeth of the gears upon opposite ends of the cylinders can be made to crowd against the teeth of their engaging gears, thereby taking up any lost motion and cause the rotary motion of one of the cylinders to 80 be accurately imparted to the other and prevent any slurring of the printing. The sheets to be printed are placed in a pile D upon a table D', carried by a slide D², held in the vertical ways D³ and connected by a link D^{3a} 85 with a crank-arm D⁴ on the shaft of the ratchet-wheel D⁵, which is intermittently rotated by a pawl D⁶ on the arm D⁷, pivoted concentrically with the ratchet-wheel and connected by a rod D⁸ with a vibrating lever 90 95 100

D⁹, actuated by a spring D¹⁰ and by an eccentric D¹¹ upon the shaft of the impression-cylinder C.

The action of the vibrating lever D⁹ is adjusted by a sleeve D¹², swiveled upon the lever and loosely inclosing the rod D⁸ between the adjustable nuts D¹³. The vibrating lever D⁹ is attached to a rock-shaft D¹⁴, journaled in the frame of the machine, to which is attached the three-pronged finger D¹⁵, extending over the pile of blanks D, so that when the blanks have been raised into the path of the finger D¹⁵ the rocking motion of the lever D⁹ is limited and the feeding motion of the table is checked until the pile of blanks is reduced, allowing the finger D¹⁵ to fall far enough to permit another tooth of the ratchet D⁵ to be engaged by the actuating-pawl D⁶ and the blanks to be again raised and held by the retaining-pawl D^{6a}. The finger D¹⁵ is preferably provided with three prongs containing an air-passage D¹⁶, Fig. 16, terminating at the ends of the prongs and upon their under side in openings or ducts D¹⁷. The ends of the prongs are flattened on their under sides, as shown in Figs. 15 and 16, and are arranged to act as pressure-fingers on the pile of blanks, the under surface of the fingers being in the same plane.

The air-passages D¹⁶ are connected by a flexible tube D¹⁸ with an air-pump consisting in the present instance of a cylinder D¹⁹, pivoted upon a stud D²⁰ and containing a reciprocating piston whose rod D²¹ is connected with an oscillating arm D²², actuated through the pitman-rod D²³ by the crank-arm D²⁴ upon the shaft of the type-cylinder B. The downward movement of the piston exhausts the air from the passages D¹⁶ at the period of contact of the pneumatic finger with the upper blank upon the pile D, causing a vacuum to be produced and the forward edge of the blank beneath the ducts D¹⁷ to be lifted by the upward motion of the pneumatic finger D¹⁵ into the position to be seized by the grippers carried by the impression-cylinder C. The grippers consist of an inner jaw E, carried by the end of a hollow shaft E', and an outer jaw F, carried by a shaft F', concentric with the shaft E', and both journaled in the ends or heads of the cylinder C, which is recessed to receive them.

To the end of the hollow shaft E' and outside the gear-wheel C⁴ is a crank-arm E², carrying a roll E³, held in contact by a spring E⁴ with a cam E⁵, attached to the inner side of one of the boxes C' and which is represented by broken lines in Fig. 3.

To the end of the shaft F', carrying the outer jaw F, we attach a pinion F², engaged by the rack F³ on the end of a lever F⁴, pivoted on the end of the impression cylinder. The rack F³ is curved concentrically with the pivot of the lever, and the lever is provided with a cam-roll F⁵, carried by the rotation of the cylinder C into contact with a fixed cam F⁶ attached to the inner side of one of the

boxes C', causing the shaft F' to be rocked and the outer jaw opened. A spring F⁷ acts against the cam F⁶, causing the jaw to close with pressure upon the paper blank when released from the cam F⁶; but in order to secure a positive action of the jaw in closing independently of the spring F⁷ we provide a cam F⁸, also attached to the box C', which serves to close the jaw. The revolution of the cylinder C will cause the jaws E and F to be independently moved into the several positions shown in Figs. 4 to 9, inclusive. As the grippers are brought into position to seize the blank raised by the pneumatic finger D¹⁵ the face of the jaw E is carried into the plane of the under side of the pneumatic finger D¹⁵ and in contact with the blank, as shown in Fig. 4. At that moment the outer jaw F by its release from the cam F⁶ is closed in the position shown in Fig. 5, causing the forward edge of the blank to be seized and carried forward by the rotation of the cylinder C. Both jaws are then moved conjointly inward until the face of the inner jaw E is brought tangential with the surface F⁹ of the cylinder, upon which a tympan is secured by any of the well-known and practiced methods. After the form has rolled in contact with the blank and the cylinder is brought into the position represented in Fig. 7 the jaws are moved outward conjointly in order to raise the advancing edge of the blank from the surface of the cylinder, so as to allow the ends of the fly-fingers G, carried upon a rocking shaft G', to pass beneath the blank. The outer jaw F is then opened, releasing the blank, which is moved upon the fly-fingers G by the cylinder C and rolls G², held by rods G³, adjustably supported by the cross-bar G⁴, and provided with elastic tires G^{2a}, between which and the surface F⁹ the blank is held after its release by the grippers. The outer jaw F is moved into position (shown in Fig. 9) so it will clear the blank held by the pneumatic finger D¹⁵. The shaft G' is rocked by the mechanism shown in Fig. 17, consisting of an eccentric G⁵ upon the shaft of the impression-cylinder, an elbow-lever G⁶, pivoted upon a fixed stud G⁷ and connected by a link G⁸ with a crank-arm G⁹ upon the shaft G', and a retractile spring G¹⁰. The printed blank is carried by the fly-fingers G over upon the shelf or "taking-off" board G¹¹, slightly inclined from a vertical position and held upon rods G¹², so that the printed blank as it is delivered by the fly-fingers will rest against the board G¹¹ with its lower edge in contact with the rods G¹², which serve as gage-rods to even the printed blanks. The upper ends of the rods G¹² are provided with the guide-rods G¹³, curved concentrically with the axis of the fly-fingers G. The taking-off board G¹¹ is adjustably held upon the rods G¹² by means of a sleeve G¹⁴, attached to the board G¹¹, and loosely inclosing one of the rods G¹² and provided with lugs to which is pivoted a lever G¹⁵, pressed by a spring G¹⁶ against the rod

G¹² and preferably having a piece of rubber or leather interposed between it and the rod. The lever G¹⁵ is readily released from the rod G¹², allowing the board G¹¹ to be moved on the 5 rod, and the friction of the lever G¹⁵ will maintain the board in position, except as it is pushed down by the movement of the fly-fingers and the accumulation of blanks upon the taking-off board.

10 In order to cause the blank held by the pneumatic finger D¹⁵ to be released at the instant it is seized by the grippers, we provide the pump-cylinder D¹⁹ with a valve H, held against its seat by a spring H', applied to the 15 valve-stem H², causing the valve to be held normally closed and preventing the admission of air through the ports H³ to the pump-cylinder D¹⁹. The valve-stem H² is pushed downward at the instant the blank is seized 20 by the gripper-jaws E and F by means of a lever I, pivoted upon a fixed stud and actuated to open the valve H by a spur I' upon the cam I², carried by the shaft of the impression-cylinder C, thereby admitting air to the pump-cylinder D¹⁹ and breaking the vacuum. The 25 pile of envelop-blanks D is placed upon the feeding-table D' with its forward or back-flap edge against the vertical guide-pins J J, held upon the shelf J', forming a portion of the 30 framework. The feeding-table is then raised into the desired position so the upper blank will be struck by the pneumatic finger D¹⁵ as the shaft D¹⁴ is rocked. The pile of blanks D as it is raised is carried behind the 35 registering gage-pins J² J², depending from the framework, and in front of the pivoted presser-bar J³, pivoted upon a stud J⁴, held in the shelf J' and having a spring J⁵ applied to press the face J⁶ against the upper 40 blanks and crowd them back against the gage-pins J² J².

To the end of the bar J³ is pivoted the block J⁷, provided with the face J⁶ and the three posts J⁸, carrying screws J⁹ with pointed 45 tips, which are adjusted to reach slightly over the pile of blanks, so the edges of those blanks which are raised by the pneumatic finger D¹⁵ will be drawn across the tips of the screws, which act as separators to separate 50 the blanks and admit air beneath the upper blank, so it will be raised by the pneumatic finger and the succeeding blanks allowed to fall back upon the pile. The upper ends of the guide-pins J J are slightly tapered, and to 55 the rocking shaft D¹⁴ are attached the fingers K K, with their under sides slightly raised above the under side of the pneumatic finger D¹⁵. As the fingers K K are carried down by the rocking of the shaft D¹⁴ they press the 60 blanks which may have been lifted by the pneumatic finger D¹⁵ down beside the guide-pins J J, whose tapered sides serve to restore any displaced blanks to their proper alignment with the pile D. The jaws E and F are 65 bifurcated, forming the double jaws a a and b b, Fig. 18, so as to seize the paper blank upon each side of the central prong c and between

the central and side prongs d d of the pneumatic finger D¹⁵, which is provided with three prongs c d d, so as to hold that portion of the 70 blank to be seized by the jaws E and F in the same plane.

The operation of the machine is as follows: The form is suitably attached to the type-cylinder B in the usual manner, and is inked by the rolls L L, to which the ink is distributed by any of the known mechanisms used for that purpose, but not shown in the drawings, as it forms no part of our present invention. The pile of blanks D is placed upon the feeding-table D' and against the guide-pins J J. The table is then raised, bringing the blanks behind the gage-pins J² J² and in front of a spring-actuated pivoted bar J³, so the face J⁶ will press the upper blanks back against the 85 gage-pins J² J² and insuring accurate registration of the upper blank. The table D' is raised into the path of the fingers K K and the pneumatic finger D¹⁵, which are brought into contact with the top blank by the rocking shaft D¹⁴, closing the air-ducts D¹⁷ as the piston of the air-pump is making its downward stroke, exhausting the air from the air-passages D¹⁶, causing the upper blank to be raised with the finger D¹⁵, and usually raising 90 several of the succeeding blanks by the clinging together of the edges of the paper. As the blanks are raised their edges are drawn over the projecting pointed screws J⁹, which separate the succeeding blanks from the top 95 blank, so they will fall back upon the pile. The revolution of the cylinder C, carrying the grippers, with their connected mechanism, around the fixed cams E⁵ will cause the jaws to be successively moved into the positions 100 already described, seizing the edge of the blank held by the pneumatic finger D¹⁵, carrying it in toward the center of the cylinder C, so as to bring it into proper alignment with the surface F⁹ to receive the impression of the 105 surface F⁹ upon the type-cylinder B. The jaws are then raised to lift the edge of the blank over the ends of the fly-fingers G, which have been brought into position tangential with the surface F⁹ of the cylinder C. As 110 soon as the edge of the blank has been caught by the tips of the fly-fingers the grippers are opened and the blank is delivered to the fly-fingers by the action of the surface F⁹ and the rolls G², and the grippers are brought into 115 proper position to seize the succeeding blank raised by the pneumatic finger D¹⁵. The fly-fingers G are vibrated by the rocking of the shaft G', carrying the printed blank over with its lower edge sliding upon the curved guide-rods G¹³, and depositing it upon the taking-off board G¹¹, with its lower edge resting upon the gage-rods G¹². As the printed blanks 120 accumulate upon the board G¹¹ the pressure of the fly-fingers G will push the board down 125 with the rods G¹². The downward motion of the pneumatic finger D¹⁵ is limited by the pile of blanks, and as the blanks are removed the angular motion of the finger D¹⁵ increases 130

until the vibrating lever D⁹ actuates the pawl D⁶, through the intermediate mechanism, as described, to move the ratchet-wheel D⁵ forward another tooth and raise the feeding-table D'. The feeding-table D' is raised through one-half a revolution of the crank-arm D⁴, or from its lower to its upper "dead-center," which limits the upward movement of the feeding-table, for when the crank-arm passes the upper dead-center the weight of the table will rotate the crank-arm and ratchet-wheel and allow the table to fall. This arrangement of the ratchet-wheel and crank as connected with the feeding-table we do not claim as a part of our present invention, but the intermediate actuating mechanism between the eccentric D¹¹ and the ratchet-wheel D⁵ we deem to be new. The prongs c d d of the pneumatic finger D¹⁵ are provided with small bosses e, located within the ducts D¹⁷, with their faces flush with the under side of the finger in order to prevent the paper from being bent or curved too much into the duct by the air-pressure.

What we claim as our invention, and desire to secure by Letters Patent, is—

1. The combination with a table upon which the blanks are supported, of a rock-shaft D¹⁴, a finger extending radially in a horizontal plane over said table and having its end forming the prong c, provided at its tip with an air-duct, prongs d, d, projecting from the side of said finger and having their ends parallel with and shorter than the prong c and having air-ducts in their ends arranged in line with the edge of an envelop-blank and having their under surfaces flattened to act as pressure-fingers to bear in the same plane upon the pile of blanks and an air-passage in said central finger communicating with said ducts, substantially as described.
2. The combination of a feeding-table upon which the blanks are supported, of the gage-pins for registering the blanks, a pivoted presser-bar J³, spring J⁵, block J⁷ pivoted on said presser-bar and having three posts J⁸ and screws J⁹ carried by said posts and having their tips overhanging the pile of blanks held on said table, substantially as described.
3. The combination of a blank-supporting table, a rock-shaft D¹⁴, radial fingers extending from said shaft over said table, a vibrat-

ing arm D⁹ attached to said shaft, an actuating-eccentric D¹¹, retractile spring D¹⁰, sleeve D¹², swiveled on said vibrating arm and enclosing a rod D⁸, rod D⁸, nuts D¹³ adjustably held on said rod, arm D⁷, connected with said rod, actuating-pawl D⁶ carried by said arm, ratchet-wheel D⁵, and intermediate mechanism between said ratchet-wheel and said blank-holding table, whereby the intermittent rotation of said ratchet-wheel will raise the table, substantially as described. 55

4. The combination of an impression-cylinder, a lifting-finger by which the blanks to be printed are raised singly, a gripping-jaw E, carried upon a shaft, journaled in said cylinder, a crank-arm attached to said shaft and a cam, actuating said crank-arm to rock said shaft and carry said jaw outward and bring its face into alinement with said lifting-finger, gripper F and means for actuating the same, substantially as described. 60

5. The combination with an impression-cylinder of the gripping-jaw E, hollow shaft E', crank-arm E² and actuating-cam by which said hollow shaft is rocked, jaw F, shaft F', pinion F², pivoted lever F⁴, provided with rack-teeth F³ engaging said pinion spring F⁷, and actuating-cam F⁶, substantially as described. 75

6. The combination of an impression-cylinder, jaws attached to shafts, journaled in said cylinder, fixed cams E⁵ and F⁶ and connecting operating mechanism between said cams and said jaws, whereby said jaws are moved in correspondence to successively seize the blank and carry it into alinement with the surface of said impression-cylinder, raise the blank from the surface of said cylinder, and finally release the blank, substantially as described. 80

7. The combination of rods G¹², board G¹¹ having a sleeve G¹⁴, lever G¹⁵, pivoted on said sleeve and engaging one of said rods, and a spring G¹⁶, substantially as described. 90
